(57) CLAIM

The ornamental design for a personal yoga mat, as shown and described.

DESCRIPTION

FIG. 1 is a perspective view of a first embodiment of a personal yoga mat engaged with a slider mat, in taken from the top.

FIG. 2 is a back view of the first embodiment of the personal yoga mat of FIG. 1 in the open configuration.

FIG. 3 is a front view of the first embodiment of the personal yoga mat of FIG. 1 engaged with a slider mat.

FIG. 4 is a left-side view of the first embodiment of the personal yoga mat of FIG. 1 engaged with a slider mat.

FIG. 5 is a right-side view of the first embodiment of the personal yoga mat of FIG. 1 engaged with a slider mat.

FIG. 6 is a top view of the first embodiment of the personal yoga mat of FIG. 1 engaged with a slider mat.

FIG. 7 is a bottom view of the first embodiment of the personal yoga mat of FIG. 1 engaged with a slider mat.

FIG. 8 is a perspective view of a first embodiment of a personal yoga mat disengaged from the slider mat, in taken from the top.

FIG. 9 is a perspective view of a first embodiment of a personal yoga mat disengaged from the slider mat, in taken from the bottom.

FIG. 10 is a back view of the first embodiment of the personal yoga mat of FIG. 1 disengaged from the slider mat.

FIG. 11 is a front view of the first embodiment of the personal yoga mat of FIG. 1 disengaged from the slider mat.

FIG. 12 is a left-side view of the first embodiment of the personal yoga mat of FIG. 1 disengaged from the slider mat.

FIG. 13 is a right-side view of the first embodiment of the personal yoga mat of FIG. 1 disengaged from the slider mat.

FIG. 14 is a top view of the first embodiment of the personal yoga mat of FIG. 1 disengaged from the slider mat; and,

FIG. 15 is a bottom view of the first embodiment of the personal yoga mat of FIG. 1 disengaged from the slider mat.

The dashed broken lines depict portions of the personal yoga mat which form no part of the claimed design. The dot-dashed broken lines represent a boundary of the claim or unclaimed environment (e.g., a wall), and forms no part of the claimed design.
